Patented Mar. 12, 1918.

UNITED STATES PATENT OFFICE.

DOSIER H. MOSTELLER, OF SACRAMENTO, CALIFORNIA.

ENVELOP-SEALER.

1,258,697.

Specification of Letters Patent. Patented Mar. 12, 1918.

Application filed January 22, 1917. Serial No. 143,567.

To all whom it may concern:

Be it known that I, DOSIER H. MOSTELLER, a citizen of the United States, residing at Sacramento, in the county of Sacramento 5 and State of California, have invented new and useful Improvements in Envelop-Sealers, of which the following is a specification.

The object of the present invention is to provide a device for sealing envelopes and 10 for moistening paper articles which shall be simple in construction, easy and convenient to operate, and which shall not get out of order.

In the accompanying drawing, Figure 1 15 is a plan view of my improved device; Fig. 2 is a side view thereof; Fig. 3 is a vertical section thereof on the line 3—3 of Fig. 1; Fig. 4 is a broken vertical section thereof on the line 4—4 of Fig. 1; Fig. 5 is a sectional view of a roller; Fig. 6 is a broken view, similar to Fig. 4, of a modification.

Referring to the drawing, 1 indicates a base upon which is secured a trough or box 2, open at the top, at one end of which is 25 pivoted, on a shaft 3, a sponge holder 4. In said sponge holder and trough is contained a sponge 6, which extends along the bottom of the trough to the end thereof, at which the sponge holder is pivoted and then extends 30 upwardly within this sponge holder. Said sponge holder is closed at the top and open at the bottom, and across the bottom of the sponge holder extend either separate wires or a continuous wire 7 extending in a 35 zig-zag direction and attached to downwardly and inwardly extending flanges 8 of said sponge holder, the latter construction being here shown.

On the top of said trough is secured a 40 guard plate 9, which is depressed at the center and perforated, as shown at 11. The object of this guard plate is to prevent any portion of the envelop from coming in contact with the water in the trough, while at 45 the same time it permits the water dropping from the sponge to run down through the perforations 11 into the trough. The sponge holder 4 has depending side portions 12, which engage fixed side stops 13, and hold 50 the sponge holder in a position elevated sufficiently above the flanges 8 to permit the gummed loose flap of an envelop to pass therebetween.

For the purpose of facilitating the insertion of the small end of the sponge holder 55 between said flap and the main body of the

envelop there is provided an extension 14 from the sponge holder beyond the side of the trough and terminating in a sharp edge 15, which is adapted to easily enter the space 60 between the flap and said body.

For the purpose of supplying the trough with water, the sponge holder is raised on its shaft 3, so that its pivoted end rests against said stops 13.

The side of the guard plate at which the envelop flap leaves the trough is extended and raised, as shown at 16, to press the moistened flap against the envelop body and seal the same.

The envelop is then passed between upper and lower rollers 17, 18, of which the upper roller is mounted upon a shaft 19, having bearings in a standard 21 and in an arm 22 supported by said standard. The lower 75 roller has at one end a trunnion 23 mounted on said standard 21, removably secured to the base 1, and is formed with a longitudinally extending central square hole 24, in which can slide a square shaft 26, which can 80 be attached by a set screw 27 to a collar 28 having a reduced portion 29 rotatable in a bearing in a standard 31 removably secured to the base 1. To the free end of said shaft 85 is removably secured a crank-shaft handle 32. This arrangement permits of the shaft being extended when wide envelopes have to be sealed.

In the modification of the invention shown in Fig. 6, the rollers 17, 18 are dispensed 90 with and a table 33 is substituted therefor.

By providing an upper roller shorter than the lower roller, either a wide or a narrow envelop can be sealed by the rollers.

I claim:

1. In an envelop sealer, the combination of a water trough, a cover supported thereby above the trough in a position in which a portion of the cover is spaced from the trough permitting an envelop flap to be 100 passed between the trough and said portion, and absorbent material held adjacent to said portion and having means for drawing water from the trough through another portion of the cover, the trough having a raised portion at one side of the cover to press the moistened flap against the envelop body. 105

2. In an envelop sealer, the combination of a water trough, a cover movably supported thereon so as to permit an envelop flap to be passed between the cover and the trough, absorbent material contained in the 110

cover and extending into the bottom of the trough, and a perforated guard plate supported by the trough and depressed in the middle and extended to form a guide for the envelop.

3. In an envelop sealer, the combination of a water trough, a cover movably supported thereon so as to permit an envelop flap to be passed between the cover and the trough, absorbent material in the cover and extending into the bottom of the trough,

and a pair of rollers between which the envelop is passed, the upper roller having a central square hole, a standard in which one end of said roller is rotatably supported, an extensible square shaft in said central hole, a collar removably secured to said square shaft, and having a reduced rounded portion, and a bearing for said rounded portion.

DOSIER H. MOSTELLER.
